William L. Brown, Lake Zurich, Ill., assignor to
Littelfuse, Inc., Des Plaines, Ill.

Filed Aug. 26, 1970, Ser. No. 24,695

Term of patent 14 years

Int. Cl. D13—03

U.S. Cl. D26—13

FIG. 1 is a front view of the fuse panel showing my new design;

FIG. 2 is a top plan view of the fuse panel;

FIG. 3 is a bottom plan view of the fuse panel; and

FIG. 4 is a side elevational view of the fuse panel. The light and heavy stippling in the drawings represent contrasting colors.

I claim:

The ornamental design for a fuse panel, substantially as shown and described.
